UNITED STATES PATENT OFFICE.

FRANK B. HOWELL, OF BUFFALO, NEW YORK, ASSIGNOR TO AMERICAN RADIATOR COMPANY, OF CHICAGO, ILLINOIS, A CORPORATION OF NEW JERSEY.

BOILER.

Original application filed October 23, 1914, Serial No. 450,672. Renewed March 8, 1921, Serial No. 450,672.

Divided and this application filed September 10, 1921. Serial No. 499,664.

My invention relates to improvements in boilers, and the same has for its object more particularly to provide a boiler which is adapted to burn bituminous or other soft fuel economically and smokelessly.

Further, said invention has for its object to provide a boiler having a secondary air supply which is so constructed and arranged that the exact volume of air necessary to insure complete combustion may be supplied to the gases liberated from the fuel, and the air so admitted to the combustion chamber be heated to the proper degree to insure the immediate ignition of the combustible gases as the same mingle therewith.

Further, said invention has for its object to provide the boiler with means for supplying secondary air which is so constructed and arranged that a part thereof will be exposed directly to the radiant heat of the fuel, and to the hot gases issuing therefrom, and another part thereof be protected by water-backed portions of the boiler.

Further, said invention has for its object to provide the boiler with means for supplying secondary air which is so constructed and arranged that the same may be readily adjusted from without the boiler in order to regulate and control the volume of air admitted to the combustion chamber.

Further, said invention has for its object to provide means for supplying secondary air to the combustion chamber which is so constructed and arranged that the same may be readily withdrawn from the boiler and another member inserted in place thereof when the said air supply member becomes worn or unfit for further use.

Other objects will in part be obvious and in part be pointed out hereinafter.

To the attainment of the aforesaid objects and ends my invention consists in the novel details of construction, and in the combination, connection and arrangement of parts hereinafter more fully described and then pointed out in the claims.

In the accompanying drawings wherein like numerals of reference indicate like parts—

Figure 1 is a front elevation showing one form of boiler embodying my said invention;

Fig. 2 is a side elevation viewed from the left hand side in Fig. 1;

Fig. 3 is a vertical section, on an enlarged scale, through one of the flues or draft passages and the fuel receptacle on line 3—3, Fig. 4;

Fig. 4 is a fragmentary horizontal section on line 4—4, Fig. 3;

Fig. 5 is a vertical section transverse to the flues on line 5—5, Fig. 3;

Fig. 6 is a detail horizontal section showing a modified form of air duct;

Fig. 7 is a fragmentary end elevation showing means for actuating the secondary air tube;

Fig. 8 is a fragmentary vertical section of the secondary air tube and the related parts;

Fig. 9 is a fragmentary horizontal section showing another modified construction of secondary air supply devices; and

Fig. 10 is an end elevation, partly in section, of the construction illustrated at Fig. 9.

In said drawings, the boiler is represented as comprising end sections 20, 21, narrow intermediate front sections 22, and deeper intermediate rear sections 23 which are so arranged in spaced relation to said front sections as to form a fuel receptacle 24 extending from one end section to the other.

The end sections 20, 21, and the intermediate front and rear sections 22, 23 are provided upon their opposite sides with laterally-extending peripheral ribs 26 which are adapted to engage with the corresponding ribs of the adjacent sections and form flues 27 intermediate said sections.

The upper and lower portions of the end and front intermediate sections, as well as the ends and the upper and lower portions of the rear intermediate sections 23 are provided with registering openings to receive nipples 29, 29^a, and 34, 35, respectively, whereby communication may be established between the several sections of the boiler.

The front intermediate sections 22 are provided at their opposite edges adjacent to the lower portions with inwardly inclined laterally-extending ribs 28 which register with the corresponding ribs of the adjoining sections to form openings 28^a for admitting the main supply of air to the fuel receptacle 24.

The lower portions of the intermediate rear sections are provided with laterally extending forwardly inclined ribs 30 which contact at their adjacent edges and serve, together with the inclined ribs 28 of the front intermediate sections 22, partly to support the mass of fuel within the fuel receptacle.

The rear intermediate sections 23 are further provided upon their opposite sides with laterally extending vertical ribs 31 whose lower ends 31^a are inclined forwardly and terminate adjacent to the forward lower edges of said sections, and to the rear of said ribs, each of said sections is provided with a large opening 32 communicating at one or the other of its ends with a smoke outlet 33.

Each intermediate rear section 23 is provided with an aperture 34 which is located at the front edge below the peripheral rib 26, at a point approximately at the height or level where the combustion of the fuel occurs within the fuel receptacle, and each of said apertures 34 is provided at its opposite ends with a peripheral collar or rib 34^a.

A secondary air supply member 35^a is disposed within the apertures 34 and extends transversely through the boiler for the purpose of furnishing an additional or secondary supply of heated air to the products of combustion issuing from the fuel receptacle.

The air supply member or tube 35^a is preferably cylindrical and is revolubly mounted within the nipples 36 located in the apertures 34 of the sections. The said air supply member 35^a may be open at one or both ends for the admission of air, and is provided with segmental slots 37 or other suitable openings adapted to register with corresponding slots or air outlets in the collars 34^a and nipples 36 through which the air may issue into the flues arranged to the rear of the fuel receptacle and extending therefrom to the smoke outlet 33. The admission of secondary air to tube may be regulated by any suitable means, as, for example, by pivoted dampers 38 arranged upon the outer side of the boiler at each of its ends. The main supply of air for supporting combustion enters at the front of the fuel receptacle through the passages 28^a between the front ribs 28, and passes transversely through the column of fuel into the receptacle. The hot gases and products of combustion pass rearwardly between the ribs 30 of the rear intermediate sections and then pass upwardly over the upper portion of the rib 31 and rearwardly and downwardly through the openings 32 to the smoke outlet 33.

The front openings may be covered by doors 30^a provided with suitable air inlet openings 40 controlled by sliding dampers 41.

In the construction represented in Fig. 6, the front air inlets of the fuel receptacle are covered by a chamber 45 which is open at the top, where a damper 46 (Fig. 10) is located. The chamber 45 may be connected by a pas-

sage 47 with one or both ends of the secondary tube 35^a. A portion of the air which enters the supply chamber 45 passes through the front openings 28^a directly into the fuel receptacle, while another portion passes to the secondary air supply member or tube 35^a. In this construction the damper 46 controls the air supply to the secondary air tube 35^a as well as to the front or primary passages 28^a. 75

The supply and return pipes leading to and from the boiler may be arranged in any desired manner. In the drawings 47^b represents the return pipe and 47^a the supply pipe.

47' denotes the fuel receptacle cover, 48 the ash pit, and 49 the door therefor.

In the secondary air inlet supply construction represented in Figs. 7, 8 and 9, the connecting nipples are omitted and the tube 50 is rotatably arranged within the flanged openings 51 of the rear sections. The faces of these flanges are partly recessed to form segmental slots 52 which correspond with the segmental slots 53 of the tube. The slots 53 may be of such length that the same can be wholly or partially closed, as desired, by rotating the tube. Suitable means are provided for rotating the tube, for instance, a hand lever 54 secured to one end of the tube, and the most desirable positions of the tube to supply the specific volume of air required for the particular fuel used are preferably indicated on the side of the boiler, as represented in Fig. 7. A hinged cover 55 or other suitable closure is provided on the side of the boiler 100 for closing the end of the tube, if desired.

In the modified construction represented in Figs. 9 and 10, the stem 60 of the hand lever 61 extends through the air chamber 62 leading to the tube and the positions of the tube 105 may be indicated directly on this chamber.

A boiler equipped with my invention is capable of burning all kinds of fuel economically and smokelessly, particularly soft or bituminous coal, without requiring frequent attention and without necessitating the frequent cleaning of the flues and heating surfaces. The smokeless combustion of soft or bituminous coal and similar fuel is insured by the additional supply of air which is admitted 110 in a highly heated state to the flame and hot gases at the point where they issue from the body of burning fuel in the fuel receptacle. The secondary air supply is highly heated in passing through the tubular air passage 115 which lies in rear of the hottest part of the burning body of fuel, and by this means is caused to mingle with the combustible gases liberated by the fuel without cooling or reducing the temperature thereof.

This application is a division of my prior application originally filed October 23, 1914, and renewed March 8, 1921, Serial No. 450,672, for which Letters Patent No. 1,393,622 were granted October 11, 1921.

Having thus described my said invention what I claim and desire to secure by Letters Patent is:

1. A boiler of the character described comprising a fuel receptacle including a transverse wall member having a secondary air passage therein at the lower extremity thereof, and flues to the rear of said wall member communicating with said fuel receptacle below said transverse wall member and said secondary air passage; said wall member including a series of separated water-backed portions arranged in spaced relation to each other along said secondary air passage and extending below the same, and a series of air outlets intermediate said water-backed portions below said secondary air passage communicating with said secondary air passage for directing the secondary air downwardly between said water-backed portions adjacent the rear of the fuel mass in a series of jets transversely of the boiler, substantially as specified. 60
2. A boiler of the character described comprising a fuel receptacle including a transverse wall member at the upper rear part thereof, flues to the rear of said wall member communicating with said fuel receptacle below said transverse wall member, and a separate member forming with a cooperating part of said wall member a transversely extending secondary air duct at the lower extremity of said wall member; said cooperating part including a series of separated water-backed portions arranged in spaced relation to each other along said secondary air duct and extending below said separate member, and a series of air outlets arranged intermediate said water-backed portions and communicating with said secondary air duct for directing the secondary air downwardly between said water-backed portions adjacent to the incandescent fuel mass to mix with the products of combustion as the same enter said flues, substantially as specified. 65
3. A boiler of the character described comprising a fuel receptacle including a transverse wall member at the rear thereof, flues extending rearwardly therefrom and communicating with said fuel chamber below said wall member, and a separate member carried by the lower portion of said wall member to provide a secondary air passage; said wall member including a series of separated water-backed portions arranged in spaced relation to each other along and extending below said separate member for supporting the same, and outlets in said wall member arranged intermediate said water-backed portions below said separate member and communicating with said secondary air passage for directing the secondary air downwardly to the products of combustion passing towards said flues, substantially as specified. 70
4. A boiler of the character described comprising a fuel receptacle including a transverse wall member at the upper rear part thereof, flues extending rearwardly therefrom and communicating with said fuel receptacle, and a separate member removably carried by the lower part of said wall member and cooperating therewith to form a transverse secondary air passage; the cooperating part of said wall member including a series of separated water-backed portions arranged in spaced relation to each other along and extending below said separate member for supporting the same, and a series of outlets in said cooperating part arranged intermediate said water-backed portions below said secondary air passage and communicating with said secondary air passage for directing the secondary air downwardly to the products of combustion passing towards said flues; said transverse secondary air passage having a portion thereof exposed directly to the incandescent fuel and the products of combustion, and other parts thereof in contact with water-backed surfaces of said boiler, substantially as specified. 75
5. In a sectional boiler, the combination with upright front sections and rear sections forming between them a fuel chamber, said rear sections being separated by flues extending from the lower portion of said chamber, of an air inlet passage extending across said rear sections and said flues and comprising collars formed on the sides of said rear sections, and an air supply tube arranged within said collars, substantially as specified. 80
6. In a sectional boiler, the combination with upright front sections and rear sections forming between them a fuel chamber, said rear sections being separated by flues extending from the lower portion of said chamber, of an air inlet passage extending across said rear sections and said flues and comprising collars formed on the sides of said rear sections, and an air supply tube rotatably arranged within said collars, substantially as specified. 85

Signed at the city of Buffalo, Erie County, in the State of New York, this 8th day of September, one thousand nine hundred and twenty-one.

FRANK B. HOWELL.
